UNITED STATES PATENT OFFICE.

WILLIAM W. JACKSON, OF NEW YORK, N. Y.

CAMP-STOVE.

1,126,220.

Specification of Letters Patent. Patented Jan. 26, 1915.

Application filed June 3, 1914. Serial No. 342,693.

To all whom it may concern:

Be it known that I, WILLIAM W. JACKSON, a citizen of the United States, and a resident of the city, county, and State of New York, have invented certain new and useful Improvements in Camp-Stoves, of which the following is a full, clear, and exact specification, reference being had to the accompanying drawing, wherein—

10 Figure 1 is an isometric view of a camp stove, constructed according to my invention, showing the stove in its most rudimentary form, in which it may be used; Fig. 2 is a side elevation of one of the interlocking tie-bars for connecting the side plates of the stove and serving also as supports for the grate, and for the top plate; Fig. 3 is a plan view of the perforated lower plate; Fig. 4 a side elevation and Fig. 5 an end 20 view thereof; Figs. 4 and 5 showing the meat roasting attachment erected; Fig. 6 is an elevation of one of the end plates; and Fig. 7 an isometric view of my improved camp stove, in its complete form, suitable for 25 cooking and for baking as well.

The difficulty with most, if not all, of the so-called camp stoves, heretofore known in the art, is in that they are too elaborate and complicated in construction, contain a great 30 many parts, and require many screws and bolts and considerable skill to erect them, and also in that, owing to this circumstance, they are quite difficult to set up, to pack and to transport.

35 The object of my invention is to provide a foldable camp stove of very simple construction, composed of a minimum number of parts, not requiring any screws, bolts and other auxiliaries for setting it up, and yet affording efficient facilities for cooking and 40 baking, and for such other uses, for which a camp stove is ordinarily required.

With this object in view my invention consists in the devising of the several parts 45 of the stove, and of the manner of combining them, so as to set up the stove as may be required for the intended uses thereof.

My improved camp stove is composed essentially of the side plates *a* and *a'*, a set 50 of interlocking tie-bars *b*, whereby the side

plates *a* and *a'* are rigidly joined together, so as to constitute, with the tie-bars, a substantial, and a rigid frame, and of the perforated plate *c*. These are the essential parts of my improved camp stove, constituting its rudimentary form as illustrated in Fig. 1, yet amply sufficient for boiling or frying or broiling of food. The end plates *d*, and eventually also a top plate *i*, are additional parts of the stove, not essential for 60 the ordinary camp cooking operations, but helpful, and affording means to equip the stove for baking of bread, etc. The foldable meat roasting attachment, constructed as shown in Figs. 3, 4 and 5, is also an additional and useful, though no essential part 65 of the stove.

The side plates *a* and *a'* are provided with slots *f*, arranged in corresponding positions, and so dimensioned, that the ends, 70 or heads *b'* of the tie-bars *b* can be passed therethrough. The shape of the tie-bars *b* is shown in Fig. 2, in a side elevation, and attention is directed to the notches *m* and the projections *b*² in the ends or heads *b'* 75 thereof. The projections *b*² of the tie-bars *b* extend at a right angle to the longitudinal axis to the tie-bars *b*, and for some distance beyond their heads. The size of the slots *f* in the side plates is 80 made corresponding to the dimensions of the heads *b'* of the tie-bars *b*, and the width of the notches *m* in the tie-bars correspond to the thickness of the side plates *a* and *a'*.

Thus when the heads *b'* of the tie-bars *b* 85 are inserted in the slots *f* and then pushed down, the side plates *a* and *a'* are engaged in the notches *m*, and thus interlocked with the tie-bars; they are then rigidly held between their heads *b'* and the straight faces 90 of the projections *b*², abutting against the inner sides of the side plates. In this manner a substantial and rigid connection is made between the side plates and the tie-bars, and the structure thus erected will be 95 amply rigid, and capable of sustaining the structure for any purpose, for which a camp stove may serve. When the perforated plate *c* is then laid on the lower tier of the tie-bars *b*, the erection of the camp stove in its 100

most rudimentary form is completed, and the stove thus made up of the parts will be sufficient for any ordinary purposes of camp cooking. When using the stove, the 5 fire is made in the space underneath the perforated plate *c* and the pots, or spiders, in which the cooking is to be done, are set upon it.

To effect a better utilization of the fuel, 10 and, eventually, also to protect the food from dust and ashes, the end plates *d* are set in position. For this purpose the end plates *d* are provided with perforations *k* and with slots *l* in their lower edges, as 15 shown in Fig. 6, and buttons *h* are provided on the sides of tie-bars *b*, and the H-shaped sockets *n* on the ends of plate *c*. The round perforations serve to enable the end plates *d* to be passed over the heads of 20 the buttons *h* and then they are dropped onto the shanks thereof; the slots *l* then engage with the cross-bars of the sockets *n*, and thus the end plates *d* are held firmly against displacement by the heads of the 25 buttons *h* and by the sockets *n*. If then the top plate *i* is set in its place, the space thus inclosed is transformed into a baking oven, into which the bread pans, or whatever else may be desired to be baked, may 30 then be set. The perforated plate *c* may, for this purpose, be eventually replaced by a solid plate, like the top plate *i*, or covered with a plate of sheet metal or the drip pan. The roasting of meat may be undertaken in 35 the same way, or the attachment, illustrated in Figs. 3, 4 and 5 may be used. This attachment comprises the two foldable brackets *o* and the rod *p*. The brackets *o* are hinged in lugs *q* and are provided with 40 stops, or feet *s*, abutting against plate *c* when erected as shown in Figs. 4 and 5. When not used, the brackets *o* are folded upon the plate *c*, as shown in Fig. 3. Bearings *o'* for the rod *p* are provided in the 45 apexes of the brackets *o*—and the rod *p* serves, when set in, to maintain the brackets *o* upstanding. For this purpose, a fixed collar *r* is set on the rod at its handle end, and a removable collar *r'* is fitted on its 50 other, tapered end. The bearing *o'* on one of the brackets *o* is closed, and the tapered end *p'* of the rod *p* is inserted therein after the collar *r'* has been slid and wedged thereon; the bearing *o'*, in the other bracket, is 55 bifurcated to permit the rod *p* to be inserted in from above. When this is done the collars *r*, and *r'* and the stops *s*, hold the brackets *o* in upright position. The end of rod *p* projects through the perforation *v* in the end plate *d*, and handle *u* may be connected thereto in the usual way for turning the rod *r* during the roasting of the meat stuck thereon.

All parts of my improved camp stove are

provided with the requisite means for joining them together in setting up the stove in any of the several variations—there are no loose screws or bolts or wedges or angles, etc., to be lost—and there are no parts of my improved camp stove that do not permit 65 of flat packing. The erecting of the stove is a most simple operation, easily and quickly performed, and the stove as well adapted for any and all cooking as may be required in a camp.

I claim as my invention:

1. A camp stove comprising two side plates having correspondingly arranged slots, tie-bars having recessed ends, fitted into the slots and depending projections, extending at right angles to the tie-bars, the tie-bars interlocking with the side plates, and a perforated plate, fitted between the side plates and supported upon the tie-bars; substantially as herein shown and described. 80

2. A camp stove comprising two side plates having correspondingly arranged slots, tie-bars having recessed ends, fitted into the slots and depending projections, extending at right angles to the tie-bars, the tie-bars interlocking with the side plates, a 90 perforated plate, fitted between the side plates and supported upon the tie-bars, buttons on the tie-bars and H-shaped abutments on the ends of the perforated plate; end 95 plates, having slotted apertures in position to engage the buttons, and open slots on their lower ends in position to engage with the abutments on the perforated plate; substantially as herein shown and described.

3. A camp stove comprising two side plates having correspondingly arranged slots, tie-bars having recessed ends, fitted into the slots and depending projections, extending at right angles to the tie-bars, the 105 tie-bars interlocking with the side plates, a perforated plate, fitted between the side plates and supported upon the tie-bars, buttons on the tie-bars and H-shaped abutments on the ends of the perforated plate; end 110 plates having slotted apertures in position to engage the buttons and open slots on their lower ends in position to engage with the abutments on the perforated plate, and a top plate, fitted between the side plates, 115 and set upon the uppermost row of tie-bars; substantially as herein shown and described.

4. A camp stove comprising two side plates having correspondingly arranged slots, tie-bars having recessed ends, fitted 120 into the slots and depending projections, extending at right angles to the tie-bars, the tie-bars interlocking with the side plates; a 125 perforated plate, fitted in, between the side plates, and supported upon the tie-bars; a foldable brackets, hinged thereto, and provided with bearings on their free ends, and with stops, abutting against the perforated

plate when the brackets are set up; a rod set in the bearings of the brackets, and provided with stops engaging with the inner side thereof to hold the brackets in upright position; plates set between the side plates above the perforated plate, and means for holding the plates in position upon the tie-

bars and upon the perforated plate; substantially as herein shown and described.
